Primary Examiner — Kevin K Rudzinski*Assistant Examiner* — Paul D Bohannon(74) Attorney, Agent, or Firm — Raven Patents, LLC; Anton E. Skaugset(57) CLAIM

The ornamental design for a chair, as shown and described.

DESCRIPTION

FIG. 1 is a front and right-side perspective view showing the new design;

FIG. 2 is a rear and right-side perspective view thereof;

FIG. 3 is a front perspective view thereof;

FIG. 4 is a right-side perspective view thereof; where the left-side perspective view is a mirror image of this view and has therefore been omitted;

FIG. 5 is a rear perspective view thereof;

FIG. 6 is a top perspective view thereof; and,

FIG. 7 is a bottom perspective view thereof.

1 Claim, 7 Drawing Sheets(56)
